MOUNTING FOR GUN SIGHTS

Rudolph Pechar, West View, Pa.

Application April 9, 1937, Serial No. 135,918

3 Claims. (Cl. 33—50)

This invention relates to telescope gun-sights; and consists in improvement in the adjustable mounting of such sights that affords, with simplicity and cheapness of structure, accuracy in service.

In the accompanying drawing Fig. I is a view partly in front elevation and partly in section of a gun-sight mounting of the invention; Fig. II is a view of the same device, partly in side elevation and partly in section, the plane of section being indicated by the line II—II, Fig. I; Fig. III is a fragmentary view in section that illustrates the engagement of the telescope in its mounting, the plane of section of Fig. III being illustrated at III—III, Fig. I; and Fig. IV is a view comparable with Fig. I, illustrating a modification in construction.

The sight includes a telescope (the position of whose cylindrical case is in the drawing indicated by broken lines at T) and a mounting therefor. The mounting includes a hoop-like frame 1, carried on a pedestal 2 that is adapted to be clamped to and removed from the barrel of a gun. When the frame is mounted on a gun barrel the hoop-like frame stands above and extends in a plane transverse to the axis of the barrel. Through the hoop-like frame extend radially (with respect to a centre in the line of sight) three extensible pins, 3, 4, and 5. Of these the pins 3 and 4 stand angularly placed, at an interval of 90° with respect to their centre in the line of sight; one extends vertically, the other horizontally; both are manually adjustable in the lines of their radial extent. The third, the pin 5, is arranged on the opposite side, and extends radially upward through the frame, on a radius that bisects the ninety-degree angle at which the pins 3 and 4 stand placed; and this pin is spring backed. These three pins, engaging the telescope (with the qualification hereinafter to be explained) at three points spaced apart circumferentially at intervals less than 180°, afford in this case its entire and sufficient support. Longitudinal adjustment in radial direction of pins 3 and 4 is permitted by the spring backing of pin 5. The vertically arranged pin 3, by its adjustment, affords in the assembled sight correction in the matter of elevation; the horizontally arranged pin 4 affords correction in the matter of windage. The structure as thus far described is of known form and organization.

In such structures longitudinal adjustment of the pins 3 and 4 is effected with sureness and precision by means of a screw-threaded engagement between frame and pin. It is desirable, in

the interest of accuracy, that the telescope itself, subject to the thrust of such adjusting pins, shall not be engaged by a pin (or pin-part) that rotates as it advances. The problem, accordingly, to which the present invention is addressed is, how by simplest construction to render the pins responsive to screw-thread adjustment, and yet to render the telescope subject only to the rectilinear movement of the pins in direction radial with respect to a centre in the line of sight.

To such end, I surround the telescope with a ring 6, and upon this ring I cause the manually adjustable pins to make immediate bearing. Additionally I may, and preferably do, provide a two-part pin, one part of which engages (with screw-thread engagement) the frame, and the other of which engages the telescope-surrounding ring; and I so elaborate the structure of ring and pin that rotation of the ring-engaging pin part is prevented.

The ring 6 is a sleeve-like member of substantial length (Fig. III) and of internal diameter slightly exceeding the external diameter of the cylindrical case of the telescope. The wall of the ring 6 is provided with an orifice 60, through which orifice, in the assembly, the tongue-like extension 50 of the spring-backed pin 5 extends. Thus the pin 5, immediately engaging the telescope, holds it firmly in place within the ring 6. It is upon this assembly of ring and telescope that fingers 3 and 4 make engagement for purposes of adjustment, it being noted that the ring is adjustable within and in the plane of the frame 1 (that is, in a plane extending transversely to the axis of the telescope) for correcting the sight in the matters of elevation and windage. The tip of the tongue 50 is rounded, as illustrated in Fig. III, and thus the engagement of the tongue upon the cylindrical case of the telescope is in effect a point-to-point engagement. The position in which the telescope T is by the pin 5 held within the ring 6 is indicated in Fig. I.

In preferred refinement of structure, the pins 3 and 4 are, as has been said, two-part members. The ring-engaging parts are the parts to which the numerals 3 and 4 are immediately applied. Surrounding these are the sleeve-like parts 30 and 40; and these sleeve-like parts 30 and 40 are externally screw-threaded and thus are rendered adjustable within screw-threaded orifices in the frame 1. The frame 1 may be formed with bosses 13, through which the screw-threaded orifices are formed. The parts 30, 40 abut upon parts 3, 4 over plane and transverse surfaces. Thus the desired radial movement is transmitted to the 55

parts 3, 4; but the parts 3 and 4 are free, so far as concerns rotation. The ring is grooved externally, as indicated at 61, and the pin parts 3 and 4 are provided with tongue-like extensions 5 31 and 41 that, in the assembly, extend into the groove. The tongue-and-groove engagement is such that the ring 6, by virtue of its rigidity, holds the engaged pin parts 3 and 4 against turning. All rotative stress is sustained by the ring; and, 10 so far as concerns the telescope T, it is subject to and is responsive only to the right-line adjustment of the pins.

The outer pin parts 30, 40 are provided with the usual heads 32, 42, that are shown to be 15 knurled, for facility in turning when grasped between the thumb and finger of the user. The enlarged heads of the pin parts 30, 40 may be skirted, as indicated at 33, 43, and these skirts, and the bosses 13, 13 upon the frame (through 20 which the screw-threaded orifices are formed, and over which the skirts extend) afford surfaces upon which graduations may be formed, as is usual.

A click device (to indicate to the user even in 25 the dark the extent of turning adjustment) may be arranged (as is usual) between the rotary and the non-rotary parts of the pins. As here shown, the non-rotary, ring-engaging parts 3, 4 carry integral extensions, one of which (the extension 30 44) is shown. This extension carries a spring-backed click block 1, that engages a complementary ratchet 8 formed on the rotary pin part 40.

Between the orifices through which the pins 3 35 and 4 extend the frame 1 may be slotted, as indicated at 9, and a set-screw 10 may be provided for tightening the slotted frame upon the pin parts 30 and 40.

Fig. IV illustrates a simpler embodiment of the 40 invention. The assembly of ring (6a) and spring-backed pin (5a) is the same as in Fig. I. The adjustment pins 3a, 4a, screw-threaded in frame 1a, are, however, simple, not two-part, and they, in 45 advance and retreat, rotate in abutment upon ring 6a. The ends 31a and 41a of the pins are advantageously convexed, and the outer surface of the ring is cylindrical and smooth, to the end that the contacts of the pins upon the ring 6a shall be, substantially, point-to-point contacts.

50 In this case also the ring 6a sustains, and by vir-

tue of its rigidity absorbs, the rotary stress, and only the right-line thrust is imparted to the telescope.

I claim as my invention:

1. In a gun-sight mounting that consists essentially of a hoop-like frame through which in assembly a telescope barrel extends and a plurality of pins adjustably borne by the frame and grouped in radial arrangement with respect to the axis of the assembled telescope barrel, the improvement herein described which consists of a ring with orificed wall, having an interior diameter greater than the exterior diameter of the telescope barrel, one of the pins in the assembly extending through the orificed wall of the ring and engaging immediately the telescope barrel and another of the pins engaging immediately the ring on the exterior surface thereof.

2. In a gun-sight mounting that consists essentially of a hoop-like frame through which in assembly a telescope barrel extends and a pin borne in screw-threaded mounting upon the frame and extending in radial direction with respect to the axis of the assembled telescope barrel, the improvement herein described which consists of a ring adapted to encircle the barrel of the assembled telescope and a tip borne by the pin and independently rotatable thereon, the said ring and the tip of the pin engaging one another in tongue-and-groove engagement.

3. In a gun-sight mounting that consists essentially of a hoop-like frame through which in assembly a telescope barrel extends and a plurality of pins adjustably borne by the frame and grouped in radial arrangement with respect to the axis of the assembled telescope barrel, the improvement herein described which consists in a ring having an interior diameter greater than the exterior diameter of the telescope barrel, one of the pins in the assembly extending radially inward 40 of the ring into engagement with the telescope barrel extending through said ring, and another of said pins including two relatively rotatable parts, with one part thereof engaging said ring in an engagement permissive of transverse ring 45 adjustment, said engagement of the ring with the last-mentioned pin part being preventative of rotation of said pin part on the axis of the pin.
